UNITED STATES PATENT OFFICE.

WILLIAM P. DUNLAP, OF MAQUOKETA, IOWA.

METALLIC BASE FOR POSTS.

SPECIFICATION forming part of Letters Patent No. 772,928, dated October 25, 1904.

Application filed February 24, 1904. Serial No. 194,985. (No model.)

To all whom it may concern:

Be it known that I, WILLIAM P. DUNLAP, a citizen of the United States, residing at Maquoketa, in the county of Jackson and State of Iowa, have invented new and useful Improvements in Metallic Bases for Posts, of which the following is a specification.

This invention has relation to metallic bases for fence-posts; and it consists in the novel 10 construction and arrangement of its parts, as hereinafter shown and described.

The object of the invention is to provide a metallic sheet of special construction which is adapted to be driven in the ground and is 15 adapted to receive within its upper end the lower end of a wooden post. The sleeve is provided with suitable perforations for the purpose of admitting air beneath the lower end of the post, and thereby preserving the 20 wood. The sleeve at its upper end is provided with a turned-back edge which at one corner is cut away so that the upper edge of the sleeve may be in continuous lines while the metal constituting the sleeve is overlapped and riveted together.

The advantages incident to the use of my invention are that posts of short length may be employed, thus effecting a saving of this material. The post being elevated above the 30 ground and having its lower end ventilated is preserved for a great length of time. The sleeve being driven into the ground, the labor of digging post-holes is avoided; and the sleeve is rigidly embedded in the earth.

35 In the accompanying drawings, Figure 1 is a perspective view of the sleeve embedded in the ground with a post located therein. Fig. 2 is a transverse sectional view of the sleeve and the lower end of the post. Fig. 3 is a 40 perspective view of the sleeve. Fig. 4 is a horizontal sectional view of the sleeve, and Fig. 5 is a perspective view of a corner of the upper edge of the sleeve.

The sleeve 1 is made of sheet metal, which 45 may be formed in tubular, rectangular, or octagonal shape. The said sleeve is open at its upper and lower ends, and the upper edge of the said sleeve is bent or folded back upon itself, as at 2. The edges of the sheet constituting the sleeve are riveted together, as at 3.

The sides of the sleeve are provided with the perforations 4. At the upper end of the sleeve and at a corner thereof which comes underneath at the overlapping edges the sheet is cut away, as at 5, and an incision 6 extends 55 down into the sheet parallel with the edge thereof. Thus the material between the incision 6 and the edge of the sheet forms a tongue. By providing the cut-away space 5 the upper edges of the sleeve may be formed 60 in continuous lines, as shown in Fig. 3—that is, the edge of the outer portion of the sheet constituting the sleeve at the overlap may be forced back in alignment with the edge of the nether portion of the sheet. Thus the upper 65 edges of the sleeve can be made to fit snugly against the sides of the post 7, which is inserted therein, as shown in Fig. 2, and thus the upper edge of the said sleeve will have a tendency to shed the moisture away from the 70 lower end of the post.

In order to erect the post, the lower end of the sleeve 1 is placed upon the ground, and a block (not shown in the drawings) is fitted into the upper end of the sleeve. By the use 75 of a sledge-hammer or maul the lower end of the sleeve is driven into the ground until the perforations 4 are just above the surface thereof. The block above referred to receives the force of the blows and preserves the sleeve 80 from distortion. The said block is then removed, and the lower end of the post 7 is driven into the upper end of the sleeve 1 until the extreme lower end of the post is just above the perforations 4. The nails 8 are then driven 85 through the perforations 9 of the sleeve 1 into the lower end of the post 7, and the parts are properly secured together.

Having described my invention, what I claim as new, and desire to secure by Letters 90 Patent, is—

1. A base for posts consisting of a continuous piece of sheet metal overlapped at its edges forming a sleeve which is of the same transverse dimensions throughout its length. 95

2. A base for posts consisting of a continuous piece of sheet metal overlapped at its edges forming a sleeve, the upper end of the sleeve being bent back upon itself.

3. A sleeve made of sheet metal having 100

overlapping edges with its upper nether corner cut away so that the upper edge of the sleeve may be in continuous lines.

4. A sleeve made of sheet metal having overlapping edges the upper end of the sleeve being bent back upon itself and being cut away at its nether corner so that the upper edges of the sleeve may be in continuous lines.

In testimony whereof I have signed my name to this specification in the presence of two subscribing witnesses.

WILLIAM P. DUNLAP.
